UNITED STATES PATENT OFFICE.

SAMUEL P. POWERS, OF WOOSTER, OHIO.

DRIVE-PIPE HOLDER.

Application filed May 14, 1923. Serial No. 638,930.

To all whom it may concern:

Be it known that I, SAMUEL P. POWERS, a citizen of the United States, residing at Wooster, in the county of Wayne and State of Ohio, have invented a new and useful Drive-Pipe Holder, of which the following is a specification.

My invention relates to improvements in drive pipe holders,—such as are used for holding pipe or casing while being pulled up or lowered in a hole, as the case may be. Its principal objects are, first to provide improved means for gripping the pipe and for releasing the same while being pulled up or lowered; second, to prevent bending of the pipe or casing in gripping and supporting the same; and, lastly, to afford means for simultaneously actuating the several slips in gripping the pipe or casing, or for releasing the grip of the slips, and freeing them simultaneously from the pipe or casing, automatically, instead of lifting and shifting them manually into desired position, as heretofore.

My invention consists of the novel combination and arrangement of parts for the accomplishment of said objects, as herein-after set forth and stated in the appended claims.

It is illustrated by the accompanying drawing, in which similar letters and figures of reference indicate like parts.

Referring thereto, Fig. 1 is a perspective view of a pipe holder embodying my invention, one side being cut away for better illustration of the mechanism; Fig. 2 is a longitudinal section of Fig. 1 on the dotted line 2—2, with the slips removed therefrom; Fig. 3 is a plan view of the slip shifting mechanism, detached; and Figs. 4 and 5 are views of the front and rear sides of the slips, respectively, detached. In the drawings A is strong metal block having end extensions a a, which rest flatwise upon supports b b, as shown in Fig. 2.

The block is provided with a tapered bore as its longitudinal center of a size sufficient to admit the introduction of the several quarter circle slips C to position therein, as shown in Fig. 1—said slips being beveled on the outside to fit the slope of the bore aforesaid, and their inner surfaces j are hollowed longitudinally to fit the pipe or casing, and are vertical to the base of the block A, making them wedge shaped, whereby the

slips tighten upon the pipe or casing, as they slide down the sloped surface of the bore of the block.

Moreover, the slips are corrugated cross-wise on their inner surfaces, and are made of hardened steel in order to effectually grip and hold the pipe or casing from falling down therethru while being pulled out of the hole in the earth.

I am aware that blocks and slips of similar construction, and operation have been heretofore used and such I do not broadly claim.

Heretofore the slips have been lifted and lowered into position by means of handles attached to their upper surfaces, and manually shifted up and down in the lifting or lowering of the pipe without any adequate means for shifting the several wedge shaped slips simultaneously, or of freeing the slips from connection with the surface of the pipe, resulting, frequently, in causing the pipe to become bent and injured by uneven operation of the slips. It is the principal object of my invention to avoid these defects, and I do so by forming longitudinal dovetailed members D, D, D, D, which are fitted to reciprocate freely up and down in corresponding dovetail grooves, as shown in Fig. 2, D'; and the slips C are actuated simultaneously by means of a circular plate B located below the block A, as shown in Fig. 1, and movably secured thereto by bolts f f passed thru the slots e, so as to rotate freely a limited distance in either direction around the outer surfaces of the slips C, respectively. The slips each have a spiral groove c cut into them near the lower end thereof, and the circular plate B is further provided with inwardly projecting studs d,

d, d, d, adapted to fit loosely within the spiral groove adjacent thereto. Removable bars g, g, are provided to serve as handles or levers for rotating the plate B; one or both of the handles may be employed by inserting the ends thereof, respectively, into the notches h.

It is apparent that by turning the plate B, when the several slips C are in position, and the studs d are in operative engagement with the respective spiral grooves c, the said slips may be simultaneously elevated, and by means of the dovetail connections aforesaid, the slips are automatically separated from their grips on the pulled up pipe or

casing, when the handles *g* are moved in one direction, and when moved in the other direction, they are simultaneously drawn down over the beveled bore of the block *A*, thereby closing around the pipe and securely holding the same within the enclosure of the slips with absolutely unyielding grip thereon.

Having thus fully described my invention what I claim as new and desire to secure by Letters Patent is—

1. In a device of the character described, the combination with a metal block having a beveled bore therein, and a plurality of dovetail grooves in the sides of the bore, of a series of slips or gripping members adapted to reciprocate vertically within the bore of the block, said slips having a dovetail tongue adapted to reciprocate within the dovetail groove of the block adjacent thereto, a spiral groove cut into the outer surface of each slip, and a circular plate surrounding said assembled slips, and provided with studs projecting inwardly and adapted to travel in said spiral grooves respectively,

when said plate is rotated in either rotary direction, substantially as set forth.

2. In a device of the character described, the combination with a metal block having a beveled bore, a plurality of dovetail grooves in the sides of the bore, a plurality of wedge-shaped and circular slips adapted to reciprocate freely, vertically, within the bore of the block, each of said slips having a dovetail tongue on its outer surface, adapted to reciprocate freely within said dovetail grooves, respectively, a spiral groove in the outer surface of each slip, and a circular plate surrounding said slips assembled in said bore, and having studs projecting inwardly adapted to travel in said spiral grooves, respectively, when the plate is rotated, substantially as set forth.

In witness whereof I hereunto set my hand this 9 day of May, 1923.

SAMUEL P. POWERS.

In presence of two witnesses:
